UNITED STATES PATENT OFFICE.

LA FAYETTE K. MILLER, OF AUSTIN, TEXAS.

IMPROVEMENT IN COTTON-HARVESTERS.

Specification forming part of Letters Patent No. 159,109, dated January 26, 1875; application filed August 10, 1874.

To all whom it may concern:

Be it known that I, LA FAYETTE K. MILLER, of Austin, in the county of Travis and State of Texas, have invented a new and Improved Machine for Picking Cotton, of which the following is a specification:

My invention consists in the employment of a system of revolving or whirling rods, a large number so arranged as to be continually going down into and emerging from the cotton-branches while in a vertical position, and while they are whirling rapidly each one upon its own longitudinal axis. The whirling motion of the rods causes the fibers of the cotton, as soon as they come in contact with the rods, to take hold of said rods or "pickers," wind round them, and remain attached till stripped off by clasps or "stripers" that slide down the rods after they come up from among the branches of cotton-stalks, and scrape the cotton into a receiver below. This entrance and exit of the pickers may be repeated one or more times before they return to the forward part of machine to go down again. The pickers cease to whirl or spin round before reaching the cotton-box, where the stripers begin to remove the cotton. The pickers, which, by reason of their whirling motion, take hold of and draw the cotton from the boll, are caused to turn by friction against broad bands that pass across the frame of machine. These bands are corrugated, so as to increase the friction against the flanges or pinions on the pickers. The bands are broad enough to act on the pickers and turn them during their descent from the top to bottom of cotton-stalks, say three and one-half feet. They travel with a speed rapid enough to give the pickers sufficient velocity to insure their attachment to all the cotton they touch the instant it is touched. The bands work on rollers, each pair standing about forty-five degrees from a perpendicular, with base journals near each other, but at top, as stated, standing inclined in opposite directions, giving the form of a trough to bands. The pickers are made of metal or other material. They are supported at their upper or base ends, where they have two journals, between which the toothed flanges or friction-pinions are placed, which pinions impart to the pickers

their whirling motion by impinging against the belts or bands. These bands turn upon rollers, as stated, which rollers have spiral grooves upon them to cause the bands to remain in position, keeping them from running or settling by their weight toward the bottom end of rollers. The pickers are wetted or oiled (if such be ever necessary) by pressing against a sponge arrangement just previous to their going down into the cotton, by which lubrication or moistening they will the more readily and the more certainly take hold of the cotton. The "stripers" are cuffs or clasps that fit around the pickers loosely enough to slide upon them easily. The stripers work in two grooves, one on each side of the pickers, by which provision the cotton is the more easily removed, and never becomes "wedged," but is all easily scraped off. The stripers pass the points of the pickers to insure the removal of the cotton. The stripers are kept up to base of pickers by spring arrangement, except when acted on in passing cotton-box. Presser levers or bars are arranged on each side of frame, arranged and connected so as to throw the stripers to points of pickers one or more times while passing receiver. These levers are to work rapidly and with long strokes, causing two or three stripings to take place while they, the pickers, are passing over cotton-box. There are two main or carrying bands that support and carry round the congeries of pickers. They work on rollers that are driven by the revolution of wagon-wheels.

Figure 1 is a side elevation of my improved cotton-picking machine, with some portions of the box removed to show the working apparatus more clearly. Fig. 2 is a sectional elevation taken on the line $x x$, and looking in the direction of arrow 1; and Fig. 3 is a front elevation of the running-gear, looking in the direction of arrow 2.

Similar letters of reference indicate corresponding parts.

A represents a couple of endless carrying-belts, arranged to run forward and backward and up and down in a wagon-box, B, by the driving-drums C, and the carrying-pulleys D, E, F, and G, the drums C being driven by a band, H, from one of the wagon-wheels.

The belts or bands A carry the pickers, which consist of a long spindle, I, suspended from a cross-bar, J, pivoted at each end to one of the bands, so that the spindles hang between the bands to enter the cotton-brush point downward as they pass down the inclines from G to C, and D to E; also so that they will withdraw in the same manner as they ascend from C to D, and E to F. At the upper end the pickers have a toothed pinion or serrated disk, K, by which they are to be revolved by the broad endless cross-bands N as they descend and ascend the inclines, the said pinions being caused to bear against the bands, and the bands being revolved by one of their drums, M, gearing with the drum C or E. These wide bands are designed to keep the pickers revolving all the time they are passing down into and rising up out of the cotton, and are therefore arranged on drums which are parallel to the inclines along which the pickers pass, and being so the drums are provided with a spiral thread contrived to work the bands upward about the same amount as they tend to work downward on the drums, thus keeping them in working position. The pickers are caused to revolve on the axis of their cross-bar J at the moment of passing over roller G, so as to point downward into the cotton by a stationary cam, O, against which a little bent arm, P, on the cross-bar comes, and they are again adjusted into the right position to pass downward from pulleys D by another starting-cam, Q. R represents the strippers for stripping off the cotton from the pickers, which gather it from the brush by winding the fibers on them as they descend and rise out of the brush, while revolving as above described. These strippers consist of a little blade or plate on opposite sides of the picker-spindles, the plates being fitted in a groove to turn with the spindles, and attached to a short tube, S, which slides up and down on the spindle, and is swiveled to the carrier T,

which is forced down at the proper time for pushing the strippers down by levers U, said levers being worked by a crank, V, and arms W. The bars T are pulled back by a spring, Y. X represents a receptacle, into which the cotton will fall when stripped from the pickers while they are passing up from C to D. Another receptacle will be provided for receiving the cotton stripped off, while the pickers are passing from E to F, and levers will be suitably arranged for working the strippers thereat. Instead of using two or more of the broad transverse bands for revolving the spindles, one single long band may be run upon suitable guide-rollers, so as to take the place of the short ones.

Having thus described my invention, I claim as new and desire to secure by Letters Patent—

1. The combination, in a cotton-harvester, of rotary or whirling pickers I and a carrier, A, substantially as herein described, for the purpose set forth.
2. The combination, in a cotton-harvester, of an endless cross-belt, N, and traveling revolving or whirling pickers I, provided with pinions or serrated disks K, substantially as herein described.
3. The combination of pickers I, pivoted supporting-bar J, endless carriers A, and stationary cams O Q, substantially as specified.
4. The strippers R, tube S, stripping-bar T, and levers U, combined with the pickers, substantially as specified.
5. The strippers arranged in grooves in the revolving pickers, and the tube S, swiveled to the stripping-bar, substantially as specified.
6. The inclined drums M for endless belts L, having a spiral rib for keeping up the said belts, substantially as specified.

LA FAYETTE KOHLER MILLER.
